(57) **CLAIM**

The ornamental design for a retro-fit quick release closure, as shown and described.

DESCRIPTION

FIG. 1 is a perspective view of a retro-fit quick-release closure showing my new design.

FIG. 2 is a left side elevation view thereof.

FIG. 3 is a right side elevation view thereof.

FIG. 4 is a front elevation view thereof.

FIG. 5 is a rear elevation view thereof.

FIG. 6 is a top plan view thereof.

FIG. 7 is a bottom plan view thereof; and,

FIG. 8 is a perspective view thereof, showing the cover in an open position.

The broken lines herein are for illustrative purposes and form no part of the claimed designs.
